UNITED STATES PATENT OFFICE.

JAMES N. HEALD, OF WORCESTER, MASSACHUSETTS, ASSIGNOR TO THE HEALD MACHINE COMPANY, OF WORCESTER, MASSACHUSETTS, A CORPORATION OF MASSACHUSETTS.

GRINDING-MACHINE.

1,006,550.

Specification of Letters Patent. Patented Oct. 24, 1911.

Application filed May 26, 1908. Serial No. 435,034.

To all whom it may concern:

Be it known that I, JAMES N. HEALD, a citizen of the United States, residing at Worcester, in the county of Worcester and 5 Commonwealth of Massachusetts, have invented a new and useful Improvement in Grinding-Machines, of which the following is a specification, accompanied by drawings forming a part of the same, in which—

10 Figure 1 is a top view of my improved grinding machine. Fig. 2 is an end view of the same, partly in section. Fig. 3 is a front elevation. Fig. 4 is a view on an enlarged scale and partly in section of the 15 feeding mechanism for one of the grinders. Fig. 5 is a horizontal section showing in detail portions of the grinder feeding mechanism.

Similar reference letters and figures refer 20 to similar parts in the different views.

My invention relates to a grinding machine arranged to grind simultaneously surfaces at angles to each other, such as the interior curved surface of a hollow cylinder 25 and one end thereof by separate grinders, comprising an improved arrangement of the means for reciprocating the grinders both with relation to each other and with relation to the work holding means, and it consists in the construction and arrangement 30 of parts as hereinafter described and pointed out in the annexed claims.

Referring to the accompanying drawings 1 denotes the supporting base of the grinder 35 to which are attached vertical plates 2, connected at the top by a transverse support forming a bridge 3, upon which are mounted journal bearings 4 for a shaft 5, having a pulley 6, driven from any convenient source 40 of power, not shown, and carrying upon one end a work holding chuck 7 of any desired pattern, in the present instance provided with radially moving jaws to hold the cylinder 8, which is rotated while its surfaces 45 *a* and *b* are being ground.

A table 9 is arranged to be reciprocated on ways 10 in a line parallel with the axis of the work holding chuck. Supported on the 50 table 9 is table 11 having journal bearings 12 for a grinder spindle 13, carrying on its end toward the chuck 7 a grinding wheel 14. The table 9 is capable of sliding on its ways 10 beneath the bridge 3, and is reciprocated by a rack 15 upon the under side of the 55 table 9, engaged by a pinion 16 on the ver-

tical shaft 17, having a suitable clutch connection 18 with a worm gear 19, engaging a worm 20 on a horizontal shaft 21. The shaft 21 is driven by a bevel gear 22 in engagement with bevel pinions 23, 23, and 60 arranged to be driven in opposite directions by the alternate attachment of the pinions 23 with a shaft 24, driven, through the usual arrangement of clutches, by change gears 25 and a pulley 26, connected with any convenient source of power, not shown. The bevel pinions 23, 23, are connected alternately to the shaft 24 by a sliding clutch 27 operated by dogs 28 in the well known manner.

The above described method of reciprocating a table is similar to that in common use and forms no part of my invention. The usual means are also provided whereby a reciprocating movement may be given to 75 the table by a hand wheel 28^a, if desired. This reciprocating movement of the table 9, carrying the grinder 14, is arranged to move the grinder back and forth over the surface to be ground, with the end of the table 9 80 itself passing under the bridge 3. The grinder 14 is rotated by the pulley 13^a and, in combination with the rotary movement imparted to the work itself, is arranged to 85 grind the surface *a* of a cylinder when brought into contact therewith by feeding mechanism, now to be described.

As shown by broken lines in Fig. 4, a rock shaft 29 is journaled in the reciprocating table 9, having two depending arms 30 and 90 31, one of which, 30, is arranged to be rocked in the usual manner by dogs 32 adjustably held on a bar 32^a, thereby rocking the shaft 29 and swinging the other arm 31 which carries a friction roll 31^a, arranged to engage 95 the sides of a V-shaped notch in a pivoted lever 33, thereby rocking the lever 33 and operating a pawl and ratchet mechanism to turn a screw 34, which engages a nut 35 upon the table 11 to move it outward. The 100 table 11 carries the grinding wheel 14, which is thereby intermittently fed toward the surface to be ground. A hand wheel 36 is provided by which the grinding wheel may be 105 brought into contact with the surface to be ground before the automatic feeding mechanism is put into operation. This method of side feed is also well known to those familiar with this class of machines and forms no part of my invention.

A second grinding spindle 37, driven by a pulley and carrying a grinding wheel 38 for grinding the end *b* of the cylinder 8, is carried upon a table 39, arranged to move in ways 40 parallel with the ways 10, in order 5 that the grinding wheel 38 may be set by the screw threaded shaft 41, Fig. 5, operated by a hand wheel 42 in a position to contact with the end of the cylinder 8. Supported 10 on the table 39 is a table 43 forming a support for the spindle 37, which is arranged to receive a reciprocating movement transverse to that of the table 39, as follows: As 15 shown in Fig. 5, the shaft 21 by which the table 9 is reciprocated is continued backward and arranged to rotate, through change gears 44 and the usual clutches, a shaft 45 provided with a worm connection with a horizontal shaft 46, upon which is slidably 20 mounted a bevel gear 47, arranged to rotate a vertical shaft 48 carrying a pinion 49, which engages a rack 50 upon the under side of the transverse table 43.

The shaft 46 is polygonal in cross section, 25 providing a sliding connection for the bevel gear 47 to allow for the movement of the table 39 in setting the grinding wheel 38.

The reverse movement of the transverse table 43 occurs when the shaft 21 is reversed 30 by the mechanism already described for reversing the movement of the table 9, so that the reciprocating movement of the table 43 in either direction is synchronous with that of the table 9. The relative distance traveled 35 between each simultaneous reverse by the tables 9 and 43 depends, therefore, entirely upon the relative speed of movement of the respective tables. This is regulated by the change speed gears 44 which consist, 40 in this instance, of three pairs of intermeshing gears *c*, *d* and *e*. The pair of gears *c* are arranged to drive the table 43 at the same speed as the table 9, to provide for work in which the surfaces *a* and *b* to be 45 ground are of approximately equal length. The other pairs of gears *d* and *e* are arranged to drive the table 43 at rates of speed of increasing slowness relative to the speed of the table 9, in order to provide for work 50 in which the surface to be ground by the grinding wheel 38 is less in length than the surface to be ground by the grinder 14. Such a condition appears in the case of the cylinder 8 which I have shown, in the present 55 instance, held by the chuck 7. Two sets of gears *d* and *e* are arranged to provide for a greater or less disproportion in the length of the surfaces *a* and *b* to be ground, where, however, the surface *b* to be ground by the 60 grinder 38 in both cases is less than the surface *a* to be ground by the grinder 14. When the surface *b* is greater, the pair of gears *c* is employed which provide for equal speed, and the grinder 14 is allowed to 65 reciprocate beyond the shorter surface *a*. In

any case, the dogs 28 are set so as not to reverse the tables 9 and 43 until the grinding of the longer surface is complete, allowing the grinder engaged upon the shorter surface to be out of contact with it during a portion of its movement. By thus driving 70 the tables 9 and 43 from the same shaft 21, and connecting the table 43 with the shaft 21 by a calculated arrangement of change gears, I am enabled to govern the relative 75 length of the reciprocating movement of the grinding wheels 14 and 38, and to adapt such movements to the character and shape of the work to be ground.

I am thus enabled to employ two grinding 80 wheels and grind surfaces at an angle to each other by my arrangement of reciprocating the grinding tools instead of the work, which is possible by my arrangement of the work supporting means, which are 85 held upon a supporting bridge 3, under which the table 9, carrying the grinding wheel 14, may pass in its reciprocating movement.

I claim,—

1. In a grinding machine, comprising a pair of rotating grinding wheels, a rotating shaft operatively connected with one of said grinding wheels to impart a feeding motion thereto, a rotating shaft operatively connected with the other of said grinding wheels to impart a feeding motion thereto, a geared connection between said shafts, and means for changing the relative speed of said shafts, whereby the relative feeding movements of said grinding wheels are varied. 90

2. In a grinding machine, comprising a pair of grinding wheels, feeding mechanism for each of said wheels, a geared connection between said feeding mechanisms, means for changing the relative speed of said feeding mechanisms, and means for simultaneously reversing said feeding mechanisms. 95

3. In a grinding machine, comprising a pair of rotating grinding wheels, a feeding mechanism for each of said grinding wheels, means for reciprocating both of said grinding wheels simultaneously, and means for regulating as desired the relative distance traveled by each of said grinding wheels 100 during said reciprocating movement.

4. In a grinding machine, comprising a pair of grinding wheels, a feeding mechanism, consisting of a rack and pinion for each mechanism of said wheels, actuating 110 shafts for each of said rack and pinion mechanisms, and a change gear connection between said actuating shafts. 120

5. In a grinding mechanism, comprising a pair of grinding wheels, rotating shafts 125 journaled at an angle to each other operatively connected with said grinding wheels respectively, means for rotating one of said shafts in opposite directions as desired, and means for connecting said shafts, thereby 130

causing the rotation of both simultaneously in the same direction.

6. In a grinding machine, the combination with a horizontal reciprocating table and a grinder mounted on said table, of a stationary work supporting bridge arranged to permit said table to reciprocate beneath it, means on said bridge for holding the work, a second horizontal table with a grinder

mounted thereon, arranged to reciprocate at 10 an angle to said first reciprocating table, and means for varying the relative length of said reciprocating movements.

Dated this 23rd day of May 1908.

JAMES N. HEALD.
